FIG. 1

FIG. 2

FIG. 3

FIG. 4

FIG. 5

FIG. 6

FIG. 7

FIG. 8

FIG. 9

FIG. 1 is a front perspective view of a trash compactor cabinet showing my new design;

FIG. 2 is a view similar to FIG. 1, but with the hopper door opened;

FIG. 3 is an enlarged, fragmentary view showing the front and a portion of the right side in perspective;

FIG. 4 is a section taken on line 4-4 of FIG. 3;

FIG. 5 is a top plan view;

FIG. 6 is a front elevational view;

FIG. 7 is a cross-sectional view taken along line 7-7 of FIG. 6;

FIG. 8 is an elevational cross-sectional view taken in the direction of line 8-8 of FIG. 6; and

FIG. 9 is a modified form of my design which has the same appearance as in FIGS. 1 through 8 except being of greater width.

The back wall is plain and unornamented.

This application is a continuation-in-part of my earlier filed application Ser. No. D. 18,897, filed Aug. 28, 1969 and now abandoned.

I claim:

The ornamental design for a trash compactor cabinet, as shown and described.
